ARTICLE OF FURNITURE

Lawrence T. Holden, Summit, N. J.

Application July 17, 1950, Serial No. 174,148

7 Claims. (Cl. 5—2)

1

This invention relates to furniture and more particularly to beds, couches and the like. In one of its more specific embodiments, it is concerned with a novel combination of bed means and storage means, e. g. a bed and a chest of drawers, wherein the bed is supported in a novel manner on the chest.

Although various combinations of a bed with other articles of furniture have been designed in the past, they have not apparently been particularly successful. This may have in some cases been due to the necessity of resorting to a compromise, whereby one or another of the desired functions was impaired. A relatively good bed might be accompanied by hard-to-use storage means or a good storage means by a bed that was hard to make.

With the various difficulties of previous structures of this type in mind, it is an object of this invention to provide a piece of furniture that may be used with ease and facility in each of its intended aspects, e. g. sleeping, storage and making.

Another object of this invention is to afford an article of furniture of the class herein contemplated, which is particularly designed and adapted to conserve space and to thus be suitable for dwellings having limited floor area.

A further object of this invention is the provision of a bed-chest or like combination, that is pleasing in its appearance, unique in its operation, and adaptable for use either singly, or in pairs, as twin beds, as a "double" bed of the so-called Hollywood type, or as a unitary three-quarter or double bed.

A still further object of this invention is to provide a bed-storage combination of this type that may be used with one longitudinal side against a wall or against another bed of this type and yet may be easily made up.

One feature of this invention resides in a combination bed and chest or storage cabinet structure, wherein the whole bed portion is adjustably cantilevered on the top of the storage portion by antifriction means, whereby it may be moved to either of two desired "normal" positions with a minimum of effort, and may be positively secured in either of these positions by detent means.

Another feature of this invention lies in a proportioning of the various parts in a manner such that a very stable structure is obtained with no sacrifice in ease of operation or facility of use.

A still further feature of this invention lies in proportioning the height thereof so that the av-

2

erage woman need not stoop over either to make the bed or to administer to the needs of a person thereon.

Another feature of this invention resides in proportioning the handles of the storage means so that they serve both as drawer pulls and as ladder steps for use by small children.

Other and further objects and features of this invention will be more fully and clearly understood from the following description of exemplary embodiments thereof taken in connection with the appended drawings in which:

Fig. 1 is a view in elevation of an illustrative embodiment of the invention showing the bed portion from one side and the chest or storage portion from its front;

Fig. 2 is a fragmentary sectional view taken on the line 2—2 of Fig. 3 and showing details of antifriction means for movably securing the bed portion to the chest portion;

Fig. 3 is a top view with parts broken away showing the antifriction means and detent means;

Fig. 4 is a sectional view taken on the line 4—4 of Fig. 1 showing details of the detent means;

Fig. 5 is a compressed, fragmented view partly in section, as indicated by the line 5—5 of Fig. 4 and showing details of the detent means, the antifriction means, and the bed spring;

Fig. 6 is an end elevational view in outline showing the bed portion extended against a wall in "sleeping" position in full outline, and extended away from the wall in "making" position in dot-dash outline;

Fig. 7 is an end elevational view in outline of two bed-chest combinations showing them as twin beds in full outline and as a "Hollywood" style double bed in dot-dash outline; and

Fig. 8 is a sectional view taken on the line 8—8 of Fig. 2 showing details of the support and guide means.

In the illustrative embodiment of the invention as shown in Fig. 1 the structure comprises a bed portion 10 and a chest portion 11. The chest or storage portion may have drawers as indicated at 12 or may be otherwise constructed to meet different needs. For example, this portion may have shelves and doors, or open shelves, or other suitable arrangements.

The bed portion may have a headboard 13 and a footboard 14 to which are secured side rails or members 15 and 16. Within this main frame of the bed is a bed spring means, which may comprise longitudinal members 20 and 21 provided

at each end with brackets. Two of the brackets 22 and 23 are shown secured respectively to opposite ends of the longitudinal member 20 (see Fig. 5). The other longitudinal member 21 is provided with like brackets. The brackets at the headboard end are connected together by a transverse member 24 and at the footboard end by a like member 25. In the device illustrated these are of angle iron. These transverse members are secured to the headboard and footboard respectively to aid in supporting the spring on the bed structure. The spring proper may be stretched between the members 24 and 25 to support the mattress 26. Fragments of the end portions of the spring are shown at 27 in Fig. 5.

Secured between both the headboard and the footboard and the respective ends of the bed spring's longitudinal members 20 and 21 are elements of the bed support means, which in the illustrated embodiment are channel members 28 extending substantially across the bed. Since these support means are the same at each end of the bed, only those at the head end will be particularly described. As may be most clearly seen in Fig. 2, the channel 28 is supported on two rollers 30 and 31. Intermediate the supporting rollers 30 and 31 is a retaining roller 32. The rollers 30, 31 and 32 are all secured on brackets mounted on the top of the chest. As shown in Fig. 2, the support rollers 30 and 31 are mounted near the longitudinal edges of the chest top and the retaining roller 32 on its center line. The supporting and retaining means may also be in sliding relation to the member 28 but roller means are preferred particularly for the supporting means. The retaining or hold-down means might well be of the sliding contact type.

In order to overcome any tendency of the bed portion to skew in its travel and to thus cause binding between the channel 28 and the supporting or retaining means or their brackets, guide means are provided. These in the illustrative embodiment are rollers 33 and 34 on the headboard end with like rollers at the other end. The guide rollers may be mounted one adjacent each supporting roller as shown in Fig. 8. These rollers may conveniently be supported on the same brackets as the supporting rollers to bear on an outside surface of the channel. Thus with a pair of guide rollers at both ends of the bed between the two channels, rectilinear movement of the bed on the chest is assured.

Secured centrally of the top of the chest is a detent means. This means, for the type of bed spring illustrated, has two like parts or arms 36 and 37 projecting from an anchoring or mounting portion 35. These arms are resilient and are provided with notches for latching to the longitudinal member 20 or 21 depending upon the direction of extension of the bed. In either of the normal extreme positions the bed portion is securely latched against movement, yet may be easily unlatched by reasonable horizontal pressure. This double latching arrangement not only makes this bed usable for sleeping in either extreme position, but is particularly useful while making the bed, to prevent it rolling away while arranging and tucking in the bed clothes.

As may be seen by inspection of Fig. 4, about one-third of the width of the bed or platform portion of the illustrated device projects beyond the chest or base in the fully extended position on either side. Thus the unloaded bed is in stable equilibrium even without the retaining roller 32. The retaining rollers react against any tendency

of the bed portion to tilt even when it is loaded at the extreme edge of the overhanging part.

In the normal and usual use of a piece of furniture of this type, the weight of the storage portion provides adequate stability against tipping. If it were desired to have a non-storage base, added stability could be attained by the provision of weights in the base.

Because the entire bed portion, including headboard and footboard, is cantilevered, and because it may be cantilevered to either side, it may very conveniently be used against a wall, as illustrated in Fig. 6. The easily movable bed portion may be rolled out from the wall for bed making without disturbing the base portion and with a minimum of energy expenditure. Furthermore, the detent means will, as noted, hold the bed portion firmly in place in the making position as well as in the sleeping position.

20 The height of a bed in accordance with this invention will ordinarily be such that the top of the mattress is about thirty inches from the floor. This makes for more convenient use by the average woman, since it is not necessary to stoop over to either make the bed or to administer to the needs of a child or infant thereon. A bed of this height is, however, not too high to be conveniently made by an average child of from seven to ten years.

30 As illustrated in Figs. 1, 3 and 4, the drawer pulls 17 may be made in bar form so that they may serve as steps of a ladder means. This provides a relatively easy means for a small child to ascend to the bed.

35 Because the bed of this invention may be locked in alternate cantilevered positions, it is particularly easy to use in pairs. For example, a pair of these structures may be used as twin beds in a relatively narrow alcove. Each bed may be normally cantilevered to a position against one of opposite walls with a relatively narrow space between them. Each may, however, be separately cantilevered to the opposite position for making, thereby efficiently using the limited 45 space. The beds in such an arrangement, would in normal use, be in accordance with the full line positions shown in Fig. 7, each against a wall as is shown for one bed in Fig. 6. For example, two beds forty inches wide, constructed in accordance with this invention, have been used in a wall-to-wall space of about eight feet. The sixteen inches in excess of the combined widths of the two beds, leaves adequate space for passage between the beds and for rolling each bed 55 portion out from the wall for making, as well as for access to drawers.

50 Pairs of these beds may also be used in the so-called "Hollywood" style with the two bed portions cantilevered toward and abutting each other, as shown in the dot-dash lines in Fig. 7. Here, as in the twin bed situation, the beds may be oppositely cantilevered to obtain a center aisle for convenience in making the beds. Because of the symmetry of the novel means which movably secures the bed portion of this device to the base or storage portion, the parts may easily be assembled so that the access side of the latter may be faced in the more convenient direction.

55 The structure and arrangement in accordance with this invention, using like elements may also be applied to a double or a three-quarter bed. In such a construction the base or storage portion would necessarily be wider to accommodate the wider bed portion. For example, a bed about fifty-eight inches wide would have a base of

about forty-four inches in width so that the normal overhang would still be about fourteen inches, as in the narrower bed. Because of the greater width the storage portion may be arranged for access at either side. A set of shorter drawers could be used on either side, or drawers on one side and shelves on the other or any other convenient arrangement.

The bed portion in this wider structure can be adapted for a temporarily greater overhang than normal to allow access to the top of the storage portion on one side. In this case a portion of the top of the storage means may have a hinged lid. In order to allow the bed to be moved far enough to obtain access to the top, the appropriate detent means will be of the passing type and stop means will be provided. The overhang in this temporary position may be nearly half of the bed width because the bed will not be occupied at this time. Detent means of the type illustrated in Fig. 4 may be employed. In this use one member as 20 will pass out of the notch in arm 36 and under this arm. The anchoring portion 35 or an extension thereof will provide a stop for the member 20.

In order to allow for this additional overhang, the support and guide rollers, at least on the side of the opening top, will be located far enough from the edge to be out of the way of the inwardly located side of the bed. The support and guide means may cooperate with the side member of the bed to serve as a stop, either in addition to the stop previously described or in place thereof. In constructions where the supporting rollers are somewhat removed from the edge of the storage compartment, the supporting and retaining elements will of course be made sufficiently strong to take care of any increased strain due to the greater distance of the edge of the bed from the support rollers when it is in the normally latched position.

Another way of using the cantilevered bed of this invention is to provide a "half" mattress on one side of the bed spring and a deck on the remainder. The mattress portion can be enclosed by suitable railings to provide a crib for a small child, and the deck with bathing facilities for the child. The railings and deck may be easily removable so that with the substitution of a full sized mattress a regular bed would be available when the child was ready for it.

Bed-chest combinations which have been made in accordance with this invention have comprised a chest and a bed frame of wood with most of the other parts of metal. The detent means may be of a strong, resilient wood, such as ash or of metal or other suitable material. The supporting, retaining and guide rollers are preferably of the ball or roller bearing type. The exterior surface of these rollers may be of a tough material such as fiber, rubber, plastic or the like, to reduce wear and to insure quiet operation. Other equivalent materials within the spirit and scope of this invention may of course be used for any of the various parts.

Instead of the type of bed spring shown in the drawings, a coil type or a box spring may be used in this device. Another possibility is a bed box with a solid bottom and a mattress of foam rubber or like material. If the spring or bed box is different from that shown in the drawings, the means cooperating with the detent will be adapted to the situation. For example, in those types having no members corresponding to the longitudinal members 20 and 21 of the illustrated modification, a latching bar could be

secured to the appropriate part on each side of the bed portion.

In the modification shown in the drawings, the various parts are secured together with bolts, nuts and screws. Obviously, special bed springs may be used and other suitable means of fabrication may be employed, depending upon the materials used for the structure, the appearance desired, and various other factors such as the requirements of quantity production, etc.

The terms "bed" or "bed portion" as herein used are intended to include the headboard, footboard, side rails, bed spring and mattress or their equivalent. Since the complete "bed" or "bed portion" is moved as a unit, there are never any sharp corners or edges of the spring or other metal parts exposed to endanger users.

It should be understood that the foregoing description and the appended drawings are intended as illustrative only and not as limiting the invention defined in the appended claims.

What is claimed is:

1. An article of furniture comprising a bed, and a storage compartment, each of substantially the same length, the bed being substantially wider than the compartment, means for securing the bed upon the compartment for limited lateral movement with respect thereto, to a position overhanging either one of the sides of the compartment.

2. An article of furniture comprising a bed, and a storage compartment, each of substantially the same length, the bed being from about one and one-third to one and one-half times the width of the compartment, means for securing the bed upon the compartment for limited lateral movement with respect thereto, to a position overhanging either one of the sides of the compartment.

3. A combination bed and storage means comprising a bed portion and a storage portion, the bed portion being of greater width than the storage portion, means for rollably mounting the bed portion upon the storage portion, whereby a part thereof may be selectively extended beyond either one of the opposite sides of the storage portion, means for preventing tilting of the bed portion with respect to the storage portion in any position of the bed portion, and means for retaining the bed portion in either extended position.

4. A device as in claim 3 in which the means for preventing tilting of the bed portion with respect to the storage portion comprises hold-down means interconnecting the two portions and located to react against the gravitational force acting upon the extended part of the bed portion.

5. An article of furniture including a bed portion and a storage portion, said bed portion being substantially wider than, but of substantially the same length as said storage portion, antifriction means for mounting the bed portion upon the storage portion, so that said bed portion may be laterally extended beyond the storage portion on either side thereof, and means for retaining the bed portion in either extreme of its extended position.

6. An article of furniture including a base and a movable platform mounted thereon, said base comprising a storage compartment, and said platform comprising a bed, said platform being of the same length as, but of greater width than said base, means for mounting the platform for lateral movement with respect to said base, and means for limiting the movement in either direction to the excess of platform width over base width.

17. An article of furniture comprising a base and a bed, the base being of substantially the same length as, but of less width than the bed, and means for mounting the bed for lateral movement on the base, including a pair of supporting rollers, adjacent each end of the base, one roller of each pair being secured to the top of the base adjacent one side thereof and the other roller of each pair adjacent the other side thereof, a retaining roller secured at each end of the base intermediate the rollers of each pair of supporting rollers, and a channel member secured across each end of the bed, a surface of each channel member resting upon one pair of the supporting

rollers, and the corresponding retaining roller bearing on an opposite surface of each channel member.
